UNITED STATES PATENT OFFICE

FERDINAND HANFF, OF BERLIN-CHARLOTTENBURG, GERMANY, ASSIGNOR TO SIEMENS-SCHUCKERTWERKE GESELLSCHAFT MIT BESCHRÄNKTER HAFTUNG, OF SIEMENS-STADT, NEAR BERLIN, GERMANY, A CORPORATION OF GERMANY

MANUFACTURE OF ELECTRIC CABLES

Application filed September 28, 1926, Serial No. 138,194, and in Germany October 5, 1925.

My invention relates to the manufacture of electric cables.

In the hitherto employed methods of manufacturing electric cables, particularly such to which the insulation is applied in several layers, it is impossible to keep the insulation covering free from wrinkles or crimps. It is well known that when applying the insulating covering the core is drawn through the cable machine by means of a pull-off wheel positively coupled with the machine and is then wound upon a drum or reel. In these processes the conductor of the cable is considerably bent which causes more or less deep wrinkles or cracks in the insulating covering. This distrubs the homogeneity of the insulation and the dielectric strength and thus reduces the working reliability of the cable.

20 The same drawback occurs when the dry cable conductor is coiled into charging baskets if their diameter is not made excessively large. The enlargement of the diameter calls, however, for extraordinarily large and 25 expensive drying and saturating or impregnating vessels which in the present day cable construction have already assumed unwieldy dimensions.

It has already been attempted to avoid or 30 at least reduce to a minimum the wrinkling or cracking of the insulation by a judicious choice of the quality of the paper, the width and the manner of wrapping it around (tight or loose, with open or overlapping tape helices). It has also been proposed to reduce the curvature of the parts over which the cable must be bent viz. the pulling-off wheel and the drum. All these expedients have, however, not produced an entirely satisfactory result.

40 My improved method eliminates all these drawbacks. This end in view is attained by avoiding the bending of the cable in the process of manufacture as long as the insulation upon it has not yet been saturated or impregnated. The cable conductors are thus passed neither over the customary pull-off wheel nor are they wound upon a cable drum. After leaving the stranding machine and 50 subsequently the insulating machine (paper

tape wrapping machine), the cable core is drawn off in the same direction and in as straight a line as possible and conducted into a vessel or chamber for drying and impregnating the insulation, preferably in one operation. This vessel has a length which corresponds with the manufacturing length of the cable.

55 In the drawings affixed hereto apparatus suitable for carrying out my improved method is diagrammatically shown by way of example. These drawings illustrate in:

Fig. 1, a complete plant for manufacturing cables,

Fig. 2, a cross-section through a drying and 65 impregnating vessel,

Fig. 3, a cross-section through a modification of such a vessel,

Fig. 4, a cross-section through a further 70 modification of such a vessel,

Fig. 5, a longitudinal section corresponding with Fig. 4, and in

Fig. 6, a sectional side-elevation of a drying chamber.

75 Like parts are indicated by like letters of reference in all the figures of the drawing.

Referring to Fig. 1 of the drawing the cable machine consists of the ordinary stranding machine *a* and the insulation applying machine *b*. The cable provided with the insulation, for instance a wrapping of paper tape, is pulled out of the cable machine by systems of positively driven roller pairs *c* in as straight a line as possible and without 80 the employment of a pull-off wheel. The cable core is then pushed along by the systems of rollers into a long vessel or chamber *d* which according to my invention may be designed as a continuous tube, which after the 85 insertion of the cable core *e* is closed at both ends by caps *f* indicated in broken lines.

To facilitate the introduction of the wrapped cable *e* into the tubular chamber *d*, a rope winch *h* is provided at the far end of the 90 chamber which serves as a relay and drags the cable through the chamber *d* by the aid of a wire cable *g*. It is, however, equally well possible to employ an endless chain 95 driven by a motor *q* for feeding the cable into 100

the chamber upon which chain the cable rests and which is driven by suitable gearing. One length of this chain may run for instance upon rollers disposed in the chamber *d*. During the drying and impregnating process which occurs in chamber *d* the links of the chain at the ends of the tube are disconnected to permit the closing of the tube by the caps *f*. The links may be disconnected in the same simple manner in which the conventional hinge link type of chain is opened, namely by pulling the cotter pin usually provided at the ends of the hinge pins, and by then pulling out the hinge or coupling pin.

An extensive tube as drying and impregnating vessel has the advantage that it is able to withstand the pressure and partial vacuum necessary for drying and impregnating the cable without excessive wall thickness. This is an important advantage in comparison with the hitherto employed boiler-shaped drying and impregnating vessels the walls of which must be made of considerable thickness. As tubes, may be employed the ordinary commercial wrought-iron tubes procurable at a comparatively very low price.

In such a tube in which a single cable or a plurality of cables may be located simultaneously, the drying and impregnating process with application of pressure or vacuum may be carried out in considerably shorter time than in the hitherto customary apparatus. By employing heating and cooling pipes within the drying tube or a heating or cooling jacket around the tube the time necessary for drying, impregnating and coating may be considerably reduced as compared with the time necessary for boiler-shaped drying and impregnating vessels.

Referring to Fig. 2 of the drawing the tube *d* is shown in cross-section with the cable *e* and pipes *k* which can be used for conducting a heating or cooling medium.

Referring to Fig. 3 of the drawing, the tube *d* containing the cable *e* is surrounded by a heating or cooling jacket *i*. This construction of the tube is particularly suitable for electric heating by distributing various heating elements over the tube. In this way a great uniformity, steadiness and regulating capacity of the heating along the entire length of the tube is ensured.

Referring to the Figures 4 and 5, the cable is shown resting upon the endless chain serving for introducing the cable into the tube. The cable *e* rests upon bolsters carrying the axles *m* of the wheels *n*, which serve at the same time as coupling pins for the links of the chain.

Fig. 6 of the drawings shows the tube *d* and the link chain travelling through it and supporting the cable *e*. The chain is provided with two removable coupling pins *m* the spacing of which is equal to the length of

the tube. Before placing the cable on the chain the chain must be so adjusted that the removable coupling pins are located at both ends of the tube after the cable has been drawn into the tube. The pins are then withdrawn after pulling the cotter pins *p*, and the chain is thereby detached from its driving gear, whereupon the hinged end covers *f* of the tube may be closed.

The insertion of the cable may be facilitated by disposing the tube at a slight angle to the horizontal. This is not especially shown in the drawings, being obvious to anyone skilled in the art. This arrangement has the further advantage that air contained in the tube which might have a detrimental effect upon the cable is able to escape during the impregnating process. In order to avoid a deviation from the straight line the entire cable machine may be disposed at the same angle of inclination to the horizontal. Since, however, even with a horizontal arrangement of the cable machine and an inclined arrangement of the tube *d* the change of direction of the cable from a straight line takes place at an infinitely large radius, no detrimental crimping or wrinkling of the cable insulation need be feared.

The fully impregnated or saturated, flexible cable can now be withdrawn from the tube and be wound upon a cable drum.

Various modifications and changes may be made without departing from the spirit and the scope of the invention, and I desire, therefore, that only such limitations shall be placed thereon as are imposed by the prior art.

What I claim is:

1. In an impregnating device for finished cables, a plurality of feed rollers for conveying the cable away from the cable machine in a straight line, a drying and impregnating tube of a length corresponding at least to the length of the manufactured cable and being disposed in straight alinement with the cable and an endless chain for guiding the cable through said tube.

2. In an impregnating device for finished cables, a plurality of feed rollers for conveying the cable away from the cable machine in a straight line, a drying and impregnating tube of a length corresponding at least to the length of the manufactured cable and being disposed in straight alinement with the cable and an endless chain for guiding the cable through said tube, the chain portion supporting the cable when in the tube being detachable from its remainder and means for closing the tube at both ends.

3. In an impregnating device for finished cables, a plurality of feed rollers for conveying the cable away from the cable machine in a straight line, a drying and impregnating tube of a length corresponding at least to the length of the manufactured cable and being

disposed in straight alinement with the cable and an endless chain for guiding the cable through said tube, the chain portion supporting the cable when in the tube being detachable from its remainder and means for closing the tube at both ends, and means for pulling the chain and cable in a straight line into and out of said tube.

4. In an impregnating device for finished cables means for conveying the cable away from the cable machine in a straight line, a drying and impregnating tube of a length corresponding at least to the length of the manufactured cable and being disposed in straight alinement with the cable and means for conveying the cable in a straight line through said tube, and pipes running in parallel through said tube for maintaining the desired temperature in the tube during the impregnating process.

In testimony whereof I affix my signature.
FERDINAND HANFF.
